S. W. Gibbs, of New York, N.Y.

Assigns, or, to

Rathbone & Co. of Albany N.Y
Letters Patent No. 1109, dated June 14, 1859.

The Schedule referred to in these Letters Patent and making part of the same.

To all whom it may concern:

Be it known that I, Sam W. Gibbs in the City of Albany, in the County of Albany and State of New York, have invented or produced a new and original ornamental design for tops and bases of sheet iron parlor, or wood Stoves, and I do hereby declare that the following is a full and exact description of the same, reference being had to the accompanying drawings and to the letters of reference, marked thereon.

A, Showing the top of said Stove, the ornamental handle C, all ornaments O, placed around the outer edge of said top also the ornament I, forming the center or raised part of said top, the whole forming in combination an ornamental top for a sheet iron parlor, or wood stove.

B. Showing the base of said Stove, all ornaments placed on the molding forming the base, are claimed as original. These ornaments are designated by the letter M, and forming in combination, an ornamental plate or base of the said Stove. The ornamental leg (placed at the edge of said base, of said Stove) marked N, is also claimed as original.

D. Showing the door and door frame of said wood Stove, all ornamental work or ornamental carving or designing of said door is claimed as original.

What I claim as my invention or production, and desire to secure by letters patent, is the combination of the different ornamental figures and forms and configuration of the moldings of the top, and base and door, of a sheet iron parlor, or wood stove, as herein set forth and described, Excol.
